WILLEBALD CONRAD STENGER, OF CHICAGO, ILLINOIS

SOUND CONTROL CHAMBER

Application filed May 5, 1930. Serial No. 450,049.

This invention relates to the amplification of sound from cone or other diaphragms of loud speakers. It is somewhat the common practice in connection with the cone type of speaker to surround the large end of the cone with, or secure this end of the cone to a baffle board which serves to prevent direct interception and partial neutralization of sound waves emanating from the opposite sides of the diaphragm. The purposes of the present invention are to provide an improved arrangement of a loud speaker unit for the purpose of initially keeping separate the waves originating at opposite sides of a diaphragm, amplifying each set of waves, bringing the waves together and delivering the same from a common sound outlet. The invention is carried out by means of oppositely arranged amplifying devices, one within the other.

Referring to the drawings Figure 1 is a front view of the loud speaker unit.

Fig. 2 is a sectional view taken on the line 2-2 of Figure 1.

Fig. 3 is a sectional view similar to that shown in Fig. 2 but illustrates a modification.

Fig. 4 is a front view of another modification.

Fig. 5 is a sectional view taken on the line 5-5 of Fig. 4.

This invention may be carried out in connection with any of the customary forms of sound reproducing diaphragms, conical, or plain. Means are provided for collecting sound waves from both sides of the vibrating diaphragm and separately conducting the waves by gradually enlarged air column devices to a common delivery opening. The waves from one side of the diaphragm are deflected reversely from their original direction and merge with the waves emanating from the opposite side of the diaphragm.

Figures 1 and 3 show angular forms of the amplifying device while Figure 4 shows the same general character of amplifier but one which is circular in outline.

In Figures 1 and 2 the vibratory cone 1 is centrally located within the amplifier, the periphery of the cone being attached to a board 2 which is provided with a center circu-

lar opening 3 through which sound waves may pass from the diaphragm 1 directly into the sound amplifying chamber 4 of the tapering air column structure formed by the end wall 5, side walls 6 and top and bottom walls 8. The outer edges of board 2 form a square extending between the top and bottom walls 8. Partition walls 9 extending from the top wall to the bottom wall are connected at their front edges with the board 2 and flare outwardly in a rearward direction toward wall 5 but terminate short of the latter. The walls 9 together with the top and bottom walls 8 therefore form a sound wave directing means for the waves delivered at the rear side of cone 1. These rearwardly directed waves are reversed in direction and deflected forwardly by impact with the rear wall 5.

Such returned waves therefore travel outwardly into the sound amplifying chamber 4, and merge with the waves originating from the opposite side of the diaphragm.

The means for vibrating diaphragm 1 are diagrammatically indicated at 10. The entire structure of the amplifying device aside from the diaphragm is preferably rigid and of non-resonant character. The inner walls and parts thereof, which are impinged by the sound waves, are covered with a pliable material 11 which may be asbestos, or a membranous substance such as leather and constituting a thin and rather soft and pliable lining throughout the sound amplifier.

Figure 3 shows a modification of the structure above described, in which the setting of the speaker unit 10 and diaphragm 1 is reversed from that shown in Fig. 2.

In this case the waves from the inside of the cone are directed against the rear wall 5 and deflected outwardly therefrom into the sound amplifying chamber 4, which also receives directly the waves sent out from the outer surface of cone 1 as directed by the walls 12 which with the walls 2 and 9 like in Figure 2 form an amplifying chamber 13.

In Figures 2 and 3 the walls 9 and 12 extend all the way between the top and bottom walls 8 of the outer amplifying device, but in Figures 4 and 5 the inner horn-shaped amplifying device 14 which is circular in cross

section is shown supported by brackets 15 extending inwardly from the outer correspondingly formed but reversely set amplifier 17.

5. Figure 5 also illustrates the use of a plain diaphragm 16. Means equivalent to the member 10 shown in Figure 2 for vibrating the diaphragm are omitted from Figure 5.

In the operation of any one of the structures illustrated sound waves from opposite sides of the diaphragm are separately conducted along sound amplifying chambers, one set of waves impinging a fixed wall and being deflected thereby into an amplifying means common to both sets of waves.

It will be understood that the sound control chamber herein disclosed, which has been described according to its operation for the purpose of sound reproduction, is of equal utility for the purpose of gathering sound waves and concentrating them upon a diaphragm when sound is recorded and transmitted. The construction may be varied in size considerably for specific purposes without sacrifice in utility or intended mode of operation.

I claim:

1. A loud speaker sound amplifying unit comprising a flaring tubular structure, the large end of the tubular structure being open and the small end closed by a fixed non-resonant wall, a smaller rigid tubular structure mounted within the first mentioned tubular structure, a diaphragm mounted across said smaller tubular structure in position so that sound waves from one side of the diaphragm are directed toward the end wall of the larger tubular structure.

2. A sound amplifying unit comprising a diaphragm and means for vibrating the same, a mounting for said diaphragm comprising a flared rigid tubular structure, the diaphragm extending across the small end of said tubular structure and the large end of said tubular structure being open, a rigid wall spaced opposite the large end of the tubular structure, and a larger tubular structure extending from said rigid wall and flared outwardly oppositely to the flare of the smaller tubular structure.

3. A sound amplifying construction comprising a rigid flared tube, the small end of said tube being closed by a rigid wall, a smaller rigid oppositely flared tubular structure within the first mentioned tubular structure, and a diaphragm extending across the small end of said smaller tubular structure.

4. A sound amplifying construction comprising a rigid flared tube, the small end of said tube being closed by a rigid wall, a smaller rigid oppositely flared tubular structure within the first mentioned tubular structure, a diaphragm extending across the small end of said smaller tubular structure, and a pli-

able surfacing material covering sound conducting surfaces of said tubular members.

5. A sound amplifying unit comprising plain angularly disposed side walls forming a flaring tubular structure, an end wall closing the small end of said tubular structure, means comprising rigid partition walls mounted within said tubular structure forming an oppositely flared inner tubular structure not extending from end to end of said first mentioned tubular structure, a diaphragm mounted within said smaller tubular structure, and means for vibrating the diaphragm.

Signed at Chicago this 1st day of May, 1930.

WILLEBALD CONRAD STENGER.
